US0D1028980S

(12) **United States Design Patent** (10) **Patent No.:** **US D1,028,980 S**
(45) **Date of Patent:** **** May 28, 2024**

(54) **KEYBOARD**

(71) Applicant: **Yuqing Xie**, Dongguan (CN)
(72) Inventor: **Yuqing Xie**, Dongguan (CN)
(**) Term: **15 Years**
(21) Appl. No.: **29/865,232**
(22) Filed: **Jul. 15, 2022**
(51) LOC (14) Cl. **14-02**
(52) U.S. Cl. **D14/392**

(58) **Field of Classification Search**

USPC D14/247, 320, 331, 333, 338, 346-347,
D14/387, 390-401, 406, 429, 455-456;
D18/1-2, 4.1-4.6, 7, 11, 12.2, 52;
D21/324, 409
CPC B41J 5/10; B41J 5/12; B41J 5/00; B41J
5/105; B41J 5/107

(57) **CLAIM**

The ornamental design for a keyboard, as shown and described.

DESCRIPTION

FIG. 1 is a perspective view of a keyboard showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 2; and,

FIG. 11 is an enlarged view of portion 11 shown in FIG. 3. The dash-dash broken lines in the drawings depict portions of the keyboard that form no part of the claimed design. The dot-dash broken lines represent boundaries of the enlarged portions and form no part of the claimed design.

1 Claim, 11 Drawing Sheets
